UNITED STATES PATENT OFFICE.

HARMANUS LANSING PERRINE, OF MILWAUKEE, WISCONSIN.

DUPLEX STEAM PUMPING-ENGINE.

SPECIFICATION forming part of Letters Patent No. 639,283, dated December 19, 1899.

Application filed April 19, 1899. Serial No. 713,664. (No model.)

To all whom it may concern:

Be it known that I, HARMANUS LANSING PERRINE, a citizen of the United States, residing at Milwaukee, in the county of Milwaukee 5 and State of Wisconsin, have invented a new and useful Improvement in Duplex Steam Pumping-Engines, of which the following is a specification.

I have designed certain improvements in 10 what is known as "cross-compound" steam ends for air and water pumps of the duplex type, and the particular improvement resides in certain parts and combinations of parts whereby a novel and advantageous operation 15 of the engine is effected. Resulting from such operation and improvements the control of the steam end is rendered easy and steady in the action of both engines, wherein the high and the low pressure pistons are caused to control to line and line the slide-valves of their 20 respective cylinders, while both of said slide-valve are carried across the ports by a single chest or driving piston, which may be arranged on the high or on the low pressure cylinder, preferably on the low.

So far as I know and can find I am the first to design and operate a cross-compound steam end through one rock-shaft and chest or driving piston so that both main pistons move 25 their respective slide-valves line to line, by direct connections to the valves, and the throw across the ports is completed by the action of a third piston acting through a lever and rock-shaft. This is the primary feature of 30 my invention and involves two steam-cylinders side by side, cross-compound, with mechanism whereby each piston has direct control over its own slide-valve to line and line, and both valves carried across the ports to widen 35 open by a single driving or chest piston.

In the accompanying drawings I have shown an engine embodying my invention in the form at present preferred by me. The following is a description of the engine shown; 45 but it will be understood that various modifications and changes may be made without departing from the spirit of my invention and without exceeding the scope of the claims.

Referring to the drawings, Figure 1 shows 50 in side elevation the high-pressure cylinder partly in section and the slide-valve for controlling the inlet and exhaust ports of said

cylinder. Fig. 2 is a cross-section on the line A B of Fig. 1 looking toward the water end of the pump and shows the rod connections 55 of the slide-valves of both cylinders and of the chest-piston of the low-pressure cylinder. Fig. 3 shows the low-pressure cylinder, partly in section, the steam-chest, the slide-valve, and the chest-piston which by its connections, it will be understood, is the means whereby the slide-valves of both engines are carried across the ports. Fig. 4 shows in partial vertical transverse section the high-pressure and low-pressure cylinders and their 60 cross-connecting pipe or by-pass for the steam-chests of the two cylinders; and Fig. 5 shows in face view the valve-seat and its ports of the low-pressure cylinder-chest.

The cross-compound steam end is applica- 70 ble to pumps for waterworks, condensers, vacuum-pumps, and air-pumps or air-compressors.

In Fig. 1 the piston of the high-pressure cylinder A is shown at the end of its inward stroke and the piston-rod connecting the water-cylinder. The steam-chest B communicates by ports in the usual manner with the cylinder A, and the slide-valve C connects by its stem *i*' to the long end of lever D, which 75 engages the cross-head *b* on the piston-rod, as seen in Fig. 2. This sliding connection of the lever with the piston provides a movable connection to accommodate the arc described by the vibratory movement of said lever. 80 This lever D is fulcrumed to the pin *c* on the crank, which is fixed to and stands downward from a rock-shaft *d*, the rocking of which is effected conjointly by its connection with the levers D, D', and F, as seen in Fig. 85 2. It will be understood that the high-pressure and low-pressure cylinders have identical valve-gear-supporting frames E, and it is upon bearings *d* *d*', fixed on the upper bars of these frames, that the rock-shaft *d* is 90 mounted across the frames. The upper end of the lever D extends above its fulcrum-pin *c* and connects and actuates the slide-valve C, so that this lever is movable on its fulcrum below its connection with the slide-valve 95 and below its connection with the rock-shaft *d*. This relation of the lever D to the crank-arm *c*' is important in its relation to the connection of the crank-arm with the auxiliary 100

or chest piston of the low-pressure cylinder, as I shall more particularly presently state.

At the low-pressure-cylinder side A' the rock-shaft d has keyed to it a short lever F, which stands upward and is connected at its upper end by link f' and rod f to the auxiliary or chest piston G of the low-pressure cylinder. To this lever F and between its connection with the rock-shaft and the chest-piston is fulcrumed on a pin e the lever D', that is connected at its lower end to a sliding bearing b^2 , seated on the frame of the low-pressure cylinder in a manner identical with the lever D of the high-pressure cylinder.

At its upper end this lever F is connected by a link g and stem g' to and actuates the chest-slide-valve H of the low-pressure cylinder A' to line and line, and this connection, as shown in Figs. 2 and 3, is important in its relation to the downward-standing crank c' , as I shall presently state. A port h at each side of the induction-port h' in the seat of the chest-slide-valve H admits steam to the chest G' of the chest-piston G, and steam admitted to its chest from the high-pressure cylinder actuates said chest-piston and through it the lever F. The piston of the high-pressure cylinder having finished its stroke to the right has brought its connected valve to line and line, as shown in Fig. 1. The auxiliary slide-valve H in the low-pressure steam-chest having a slight lead is admitting steam to the chest of the chest-piston G by the small port h , and the said valve G is thereby caused to move the lever F to the right, while the crank c' by its pivotal connections is moved to the left, carrying with it the lever D, and through its connecting-link i' moves the slide-valve C to the left to wide-open port, reversing the stroke and exhausting into the low-pressure steam-chest and cylinder through the cross or pass-over pipe I. (See Fig. 4.) By this arrangement the two pistons pass each other in the center of the stroke and in opposite directions.

The lever F and the crank c' stand in reverse direction, so as to give the opposite directions to the piston in passing the center.

It will be readily understood that by the arrangement of valve-gear the chest-piston actuates the slide-valve of the high-pressure cylinder and at the same time controls the slide-valve of the low-pressure cylinder, while each cylinder-piston controls its own slide-valve to line and line, and that the said slide-valves of each cylinder move to wide-open ports by the action of the one auxiliary steam-chest piston that is controlled by the main lever of one of the steam-cylinders.

Referring to the functions of the lever D, connecting the piston-rod of the high-pressure cylinder, and of the lever F, connecting the auxiliary chest-piston of the low-pressure cylinder, it will be noticed that the connections of said levers are such as to cause them to move together in the same direction with each movement of the piston-rod to which

the lever D is connected, while the connections of the lever D' with the lever F and the slide-valve of the low-pressure cylinder are such as to cause the said lever D' to move in a reverse direction to the lever D to produce the operations stated.

In Fig. 4, I indicates the steam-supply port of the pass-over pipe for the low-pressure slide-valve and B³ the exhaust, while in Fig. 1, B² indicates the exhaust for the high-pressure-cylinder slide-valve.

It is obvious that the chest driving-piston need not be confined in its location to the low-pressure steam-chest, as it may be arranged upon and actuated by steam from the high-pressure chest; but I prefer the arrangement shown.

As a means of starting the engine a bypass connection may be made to the pass-over pipe for admitting live steam to the low-pressure cylinder.

I claim—

1. In a cross-compound direct-acting steam pumping-engine, and in combination with high and low pressure steam-cylinders side by side, their pistons and slide-valves, a driving chest-piston on the low-pressure cylinder in direct communication with an auxiliary slide-valve controlled by the low-pressure piston, the pistons, and slide-valves of both cylinders and the driving chest-piston connected by means of a rock-shaft having an arm at each end, a lever connecting each arm, the piston-rod of each cylinder and the slide-valve of each cylinder, one of said arms connecting said driving chest-piston, whereby to cause the latter to be actuated by the exhaust-steam from the high-pressure cylinder, to carry the slide-valves of each cylinder across the ports to wide open, and each cylinder-piston to have direct control over its own slide-valve.

2. In cross-compound steam pumping-engines, and in combination with high and low pressure cylinders, their pistons, and slide-valves, of valve-actuating gear consisting of the lever D connected to the piston and slide-valve of the high-pressure cylinder, the rock-shaft d having the downward-standing crank-arm c' , on the pin e of which said lever is fulcrumed, the upward-standing lever F on the said rock-shaft, the auxiliary piston connecting the upper end of said lever F, and the lever D' connected by its long end to the cross-head of the piston-rod of the low-pressure cylinder, and fulcrumed on said lever F between its rock-shaft and its connection with the auxiliary piston, whereby the slide-valves are controlled to line and line, and moved to wide-open ports, in the way described.

3. In a cross-compound steam pumping-engine, and in combination with high and low pressure cylinders, their pistons and slide-valves, of the lever D connecting the piston and slide-valve of the high-pressure cylinder, the lever D' connecting the piston and slide-valve of the low-pressure cylinder, the auxil-

iary piston of the latter, the transverse rock-shaft, having the crank-arm c' at one end connecting the lever D and the lever F on the other rock-shaft end, connecting the auxiliary piston, and the lever D', arranged to operate substantially as described.

4. The combination in a cross-compound direct steam pumping-engine, the high and low pressure cylinders side by side, their pistons and slide-valves, the transverse rock-shaft d having the crank-arm c' on one end and the lever F on the other and standing in reverse vertical direction, the lever D pivotally connecting the said crank-arm and the piston cross-head of the high-pressure cylinder, the lever D' pivotally connecting the piston cross-head and the slide-valve of the low-pressure cylinder and meditately connecting the said lever F of the driving or chest piston for operation in the way described.

5. The combination of the high and low pressure cylinders side by side, their pistons and slide-valves, with the rock-shaft having the crank-arm c , the lever D connecting the said crank-arm, the slide-valve and piston-rod of the high-pressure cylinder, the lever F on the rock-shaft connecting the auxiliary piston, and the lever D' connecting said lever F and the piston-rod of the low-pressure cylinder, the said valve-gear connections being disposed and actuated to cause one engine to operate its own valve and the valves of the other engine.

6. In combination in a cross-compound direct steam pumping-engine, the high and low pressure cylinders side by side, the levers D, D' connecting the pistons of said cylinders, the transverse rock-shaft having on one end the hanging crank-arm c' connecting the lever D and on the other end the lever F connecting meditately of its length with the lever D' whereby the said pistons are caused to control its own slide-valve, and the driving or chest piston connecting the lever F whereby the slide-valve of each cylinder is caused to be moved to wide-open ports.

7. In a duplex steam pumping-engine and in combination with high and low pressure cylinders, their pistons and slide-valves, and valve-gear arranged and connecting said slide-valves whereby one engine is caused to actuate its own slide-valve and the slide-valve of the other engine, of the auxiliary piston having direct connection with the slide-valve of the low-pressure cylinder through lever F, and connected to and actuated by said gear, whereby said auxiliary piston is actuated to cause the slide-valves of both cylinders to be carried across their ports.

In testimony whereof I hereunto sign this 60 specification.

HARMANUS LANSING PERRINE.
